UNITED STATES PATENT OFFICE

2,544,793

AUTOMATIC DRIFTING VALVE

Edmund P. Kelly, Chicago, Ill.

Application February 20, 1948, Serial No. 9,807

1 Claim. (Cl. 121—134)

1 My invention relates to improvements in automatic drifting valves for steam locomotives and has for one object to provide means which will automatically admit to the cylinders of the locomotive, air in sufficient volume to prevent the formation of a vacuum as a result of the drifting movement of the locomotive with the throttle closed, which vacuum unless prevented, would cause hot gases to be drawn in from the front end of the smoke box of the locomotive through exhaust passages.

I propose to apply to the exhaust side of the main steam valve at any suitable point, a drifting valve which will automatically, when the throttle is closed and steam pressure closed off, admit air to the exhaust side of the engine thus preventing the formation of any such vacuum.

My invention is illustrated more or less diagrammatically in the accompanying drawings, wherein:

Figure 1 is a section through the valve shaft and part of the cylinder and piston showing my drifting valve in elevation;

Figure 2 is a cylinder section on an enlarged scale, of my valve.

Like parts are indicated by like characters in the drawings.

1 is the cylinder; 2 the piston; 3 is the cylinder ports which respectively connect the valve chest with each end of the cylinder. 4 is the valve chest which contains ported valve seat sleeves 5, 6. These ports being in register with the ports 3, 3. 7 is a spool valve having enlarged heads 8, 9 adapted to travel in the sleeves 5, 6 to open and close the ports in those sleeves. 10 is the valve stem. 11 a cap closing the valve chest on the high pressure side and recessed as at 12 to receive packing not here shown as it forms no part of my invention. 13 is a cap closing the opposite end of the valve chest. 14 is the high pressure side of the valve chest and 15 the high pressure steam pipe from the boiler. The exhaust from the low pressure side of the valve chest 16 is not illustrated as it also forms no part of my invention.

The cap 13 is centrally apertured as at 17. Closing that aperture is a ball ring 18 held in place on the cap or valve chest head 13 by cap screws 19. Extending outwardly from the ball ring 18 are a series of supporting brackets 20 which carry a collar 21 to which is bolted the apertured ring 22 by means of bolts 23. The apertured ring 22 carries the drifting valve cylinder 24 flanged as indicated to engage the ring 22. 25 is packing

2 within the cylinder 24 adapted to be compressed by the gland 26 and cap screws 27.

28 is a hollow piston contained within the cylinder 24 closed at the outboard end. This piston carries a valve disc 29 about the periphery of which is a valve ring 30.

Extending outwardly from the ball ring 18 are a series of lugs 31 which support a shield 32; there being apertures between the shield 32, the lugs 31 and the ball ring 18 to contain netting or screening or other material to prevent the entrance into the valve chest of foreign material.

33 is a spring fitted at one end of the shield 32 and the other end of the hollow piston 28. 34 is a pipe that leads from the end of the cylinder 24 to the high pressure side of the valve chest. 35 are studs threaded in the collar 22 which may be screwed inwardly if desired to overcome the spring pressure 33 and seat the valve 29, 30.

20 It will be understood that under ordinary operating conditions when steam is applied to the high pressure side of the valve chest 14 through the steam pipe 15, the steam passes through the pipe 34 into the drifting valve cylinder 24 through the passage of piston 28, overcoming the spring 33 closing the aperture through the ball ring 18. Under these circumstances, the usual valve movements take place; the locomotive operates in the usual manner because we have on one side of the piston 28, high pressure steam direct from the boiler and on the other side of the piston only exhaust pressure which is little if any above atmospheric.

35 If now, the engineer, closes the throttle, shutting off the steam supply to the high pressure side of the valve chest and the engine drifts along under the weight of the train in the usual manner, since no steam is being fed to the piston through the valve chest and since the piston continues to work back and forth and the steam valve continues its usual cycle, a vacuum is set up in the exhaust side of the valve chest and since the exhaust side of the valve chest is directly connected through the exhaust nozzle (not shown), through the smoke box at the forward end of the boiler, this vacuum will draw hot gas, soot, cinders, etc., through the valve chest, thus causing a very dangerous and unsatisfactory condition. However, when the engineer turns off the steam by closing the throttle, the same time pressure drops on the outboard end of the piston 28 the spring 33 immediately opens valve making a direct passage from the exhaust side of the valve chest to the atmosphere and so this vacuum 40 is effectively avoided and this situation prevails

until the engineer again opens the throttle when immediately, the drifting valve closes and the engineer operates in the usual manner.

The sole purpose of the studs 35 is to provide a positive closure for the valve chest, if that should be necessary or desirable, as for instance in connection with hydrostatic tests and the like.

Although I have shown an operative form of my invention, it will be recognized that many changes in the form, shape and arrangement of parts can be made without departing from the spirit of the invention, and my showing is therefore to be taken as, in a sense, diagrammatic.

I claim:

In combination, a valve chest for steam locomotives and the like, a reciprocating cylindrical valve, dividing the chest into high pressure steam and low pressure exhaust sections, an aperture in the wall of the chest between the exhaust section and the outer atmosphere, a bracket masking said aperture, a sleeve on the bracket open at one end to the interior of the valve chest, closed at the other end and circumferentially apertured outside the chest, a sleeve valve adapted to encircle the apertured sleeve, a cylinder carried by the bracket, a piston reciprocable in the cylinder

carrying the sleeve valve, yielding means tending to hold the valve in open position, a steam connection between the cylinder and the steam section of the valve chest whereby when steam under pressure is admitted to the chest it enters the cylinder, overcomes the spring and seats the valve.
